(57) **CLAIM**

The ornamental design for a cupcake carrier, as shown and described.

DESCRIPTION

FIG. 1 is a top view of a cupcake carrier showing our new design in a closed position;

FIG. 2 is a side view thereof;

FIG. 3 is a bottom view thereof;

FIG. 4 is a front view thereof;

FIG. 5 is an isometric view thereof;

FIG. 6 is an exploded front view thereof;

FIG. 7 is an exploded isometric view thereof; and,

FIG. 8 is an exploded side view thereof.

The broken lines in the drawing views of FIGS. 1, 4, 5, 6 and 7 of the handle represent portions of the cupcake carrier that form no part of the claimed design.

1 Claim, 8 Drawing Sheets
